[57] CLAIM

The ornamental design for a film splicer, as shown and described.

DESCRIPTION

FIG. 1 is a front, top and left side perspective view of a film splicer showing our new design, in closed, film splicing condition;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof; and,

FIG. 8 is a perspective view thereof in open condition.
